(57) **CLAIM**

The ornamental design for a control panel for positive airway pressure delivery device, as shown and described.

DESCRIPTION

FIG. 1 is a perspective view of a control panel for positive airway pressure delivery device according to our design; and, FIG. 2 is a top view thereof.

The omission of the bottom view is intended to convey that the element(s) depicted is/are plain and unornamented in that omitted view, or that the particular ornamental appearance in that view is simply not claimed.

The broken lines shown in the figures represent portions of the control panel for positive airway pressure delivery device that form no part of the claimed design.
